(57) **CLAIM**

The ornamental design for a fill cap set and computer module cover for a motorboat engine, as shown and described.

DESCRIPTION

FIG. 1 is a perspective view of the fill cap set and computer module cover for a motorboat engine as positioned on a motorboat engine (the motorboat engine being shown in dotted lines).

FIG. 2 is a top plan view of the fill cap set and computer module cover for a motorboat engine.

FIG. 3 is a bottom plan view of the fill cap set and computer module cover for a motorboat engine.

FIG. 4 is a front elevation view of the fill cap set and computer module cover for a motorboat engine.

FIG. 5 is a back elevation view of the fill cap set and computer module cover for a motorboat engine.

FIG. 6 is a left side elevation view of the fill cap set and computer module cover for a motorboat engine; and,

FIG. 7 is a right side elevation view of the fill cap set and computer module cover for a motorboat engine.

The broken line showing is for illustrative purposes only and forms no part of the claimed design. In addition, broken line lettering has been placed on each of the fill caps and the computer module cover to identify the individual fill caps and computer module cover throughout the figures. This broken line lettering is for illustrative purposes only and forms no part of the claimed design.
